Primary Examiner — Messina L Smith(74) *Attorney, Agent, or Firm* — Raphael Bellum PLLC(57) **CLAIM**

The ornamental design for a flosser, as shown and described.

DESCRIPTION

FIG. 1 is a perspective view of a flosser showing the new design.
 FIG. 2 is a front view of the flosser of FIG. 1.
 FIG. 3 is a back view of the flosser of FIG. 1.
 FIG. 4 is a left side view of flosser of FIG. 1.
 FIG. 5 is a right side view of flosser of FIG. 1.
 FIG. 6 is a top view of flosser of FIG. 1; and,
 FIG. 7 is a bottom view of flosser of FIG. 1.

The broken lines shown in the drawings depict portions of the flosser that form no part of the claimed design.

1 Claim, 4 Drawing Sheets(56)
